RAILWAY SWITCH OPERATING APPARATUS

Earl M. Allen, Swissvale, and Edwin G. Little, Wilkinsburg, Pa., assignors to The Union Switch & Signal Company, Swissvale, Pa., a corporation of Pennsylvania

Application March 28, 1936, Serial No. 71,478

6 Claims. (Cl. 246—258)

Our invention relates to railway switch operating apparatus, and particularly to improvements in apparatus of the type described and claimed in Letters Patent of the United States No. 1,791,799, granted to J. P. Coleman, on February 10, 1931.

We will describe two forms of apparatus embodying our invention, and will then point out the novel features thereof in claims.

In the accompanying drawings, Fig. 1 is a view, partly in section and partly diagrammatic, illustrating one form of apparatus embodying our invention. Figs. 2 and 3 are detail sectional views taken on the lines II—II and III—III, respectively, of Fig. 1. Fig. 4 is a view, partly in section and partly diagrammatic, illustrating a modification of a portion of the apparatus shown in Fig. 1.

Similar reference characters refer to similar parts in each of the several views.

Referring first to Fig. 1, the switch operating apparatus embodying our invention is here shown as comprising a suitable casing 1 provided at one end with a pair of laterally spaced parallel cylinders 2^a and 2^b, and at the other end with a pair of laterally spaced parallel cylindrical guideways 3^a and 3^b which align axially with the cylinders 2^a and 2^b, respectively. The cylinders 2^a and 2^b are closed at their outer ends by means of a cylinder head 4, and communicate at their inner ends with a transmission compartment 7, which compartment also communicates with the inner ends of the guideways 3^a and 3^b. Pistons 5^a and 5^b are reciprocably mounted in the cylinders 2^a and 2^b, and are attached to the ends of rack bars 6^a and 6^b, respectively. These rack bars extend through the transmission compartment 7 for intermeshing engagement with the opposite sides of a gear wheel 8, and are guided at their free ends by means of cylindrical guides 9^a and 9^b which are slidably mounted in the guideways 3^a and 3^b, respectively. The gear wheel 8 is secured to a vertically extending switch actuating shaft 10 which is journaled in suitable bearings not shown, and fixed to the shaft 10 is a switch actuating crank 11. This crank carries a roller 12 which cooperates with a transversely extending slot 13 formed in a switch operating rod 14. The switch operating rod 14 is slidably mounted in the lower part of the casing 1, and is adapted to be connected at one end or the other with the movable rails of a track switch S which is shown diagrammatically in the drawings.

The left-hand ends of the rack bars 6^a and 6^b are provided with locking dogs 15^a and 15^b which cooperate with suitable apparatus including a

lock rod L for locking the switch S in its two extreme positions. This locking apparatus forms no part of our present invention, and may, for example, be similar to that which is described in detail in the previously referred to Coleman Patent No. 1,791,799. It is believed to be unnecessary, therefore, to describe this locking apparatus in this application.

The pistons 5^a and 5^b are so arranged in the cylinders 2^a and 2^b that, when one piston is at the end of its stroke in one direction, the other piston will be at the end of its stroke in the other direction. Fluid pressure is adapted to be selectively admitted to the right-hand ends of the cylinders 2^a and 2^b through ports 16^a and 16^b formed in the cylinder walls, in a manner which will be described in detail hereinafter, and it will be apparent that, if fluid pressure is admitted to cylinder 2^a through the port 16^a when the parts are in the positions in which they are shown in Fig. 1, piston 5^a will move rack bar 6^a toward the left, thereby rotating gear wheel 8 in a counter-clockwise direction, and hence moving rack bar 6^b and piston 5^b toward the right. Similarly, if fluid pressure is admitted to cylinder 2^b through port 16^b when the parts are in their last named positions, piston 5^b will move rack bar 6^b toward the left, thereby rotating gear wheel 8 in a clockwise direction, and hence moving rack bar 6^a and piston 5^a toward the right. It follows that the gear wheel 8 and shaft 10 can be given either a counter-clockwise or a clockwise rotation by admitting fluid to the proper cylinder 2^a or 2^b. When the shaft 10 is rotated in a clockwise direction to its one extreme position, the switch operating rod 14 is moved upwardly by the roller 12 to an extreme position in which the switch occupies its full normal position and, conversely, when the shaft 10 is rotated in a counter-clockwise direction to its other extreme position, the operating rod 14 is moved downwardly to an extreme position in which the switch occupies its full reverse position.

Operatively connected with the switch operating shaft 10 is a cam member 17 forming part of a circuit controller C. This circuit controller is of well-known construction, and may, for example, be similar to that shown and described in the previously referred to Coleman Patent No. 1,791,799. Briefly described, this circuit controller comprises two pivoted bell crank levers 18^a and 18^b provided with rollers 19^a and 19^b, respectively, and biased by means of a spring 20 to such positions that the roller 19^a will enter a notch 17^a formed in the periphery of the cam

- member 17 when and only when the switch operating apparatus occupies its extreme normal position in which it is shown in the drawings, and that, the roller 19^b will enter the notch 17^a when 5 and only when the switch operating mechanism occupies its extreme reverse position. The lever 18^a is operatively connected with two movable contact fingers 21^a and 24^a which cooperate respectively with fixed contact members 22^a, 23^a, 10 and 25^a, 26^a in such manner that, when the roller 19^a is within the notch 17^a, the finger 21^a will engage the member 22^a to close a contact 21^a—22^a and the finger 24^a will engage the member 25^a to close a contact 24^a—25^a, but that, when 15 the roller 19^a is forced out of the notch 17^a, the finger 21^a will then engage the contact member 23^a to close a contact 21^a—23^a and the finger 24^a will engage the contact member 26^a to close a contact 24^a—26^a. In a similar manner, the lever 18^b is operatively connected with two movable contact fingers 21^b and 24^b which cooperate respectively with fixed contact members 22^b, 23^b, 20 and 25^b, 26^b to close contacts 21^b—22^b and 24^b—25^b or 21^b—23^b and 24^b—26^b according as 25 the roller 19^b occupies the notch 17^a or is forced out of this notch.

Formed in the right-hand end of the casing 1 between the cylinders 2^a and 2^b are auxiliary cylinders 27^a and 27^b which are closed at their outer ends by the cylinder head 4, and which communicate at their inner ends with a compartment 28 that is also formed in the right-hand end of the casing 1 between the cylinders 2^a and 2^b. The auxiliary cylinders 27^a and 27^b also communicate 30 intermediate their ends with the cylinders 2^a and 2^b through the medium of the previously referred to ports 16^a and 16^b, and have mounted therein reciprocating pistons 29^a and 29^b which are so constructed that these pistons will blank the ports 16^a and 16^b when the pistons occupy their extreme right-hand or retracted positions, but not when these pistons occupy their extreme left-hand or projected positions. The pistons 29^a and 29^b operate piston rods 30^a and 30^b which extend 35 into the transmission compartment 7 through guideways 31^a and 31^b formed in the end wall 32 of the compartment 28, and are pivotally connected within the transmission compartment to lock operating levers 33^a and 33^b. The lock operating levers are pivotally supported on fixed pivot pins 34^a and 34^b, and have formed integral therewith locking dogs 35^a and 35^b which cooperate with notches 36^a and 36^b formed in the rack bars 6^a and 6^b below the rack teeth, as shown in connection with the rack bar 6^b in Fig. 3. The parts are so proportioned that the notch 36^a in the rack bar 6^a will align with the locking dog 35^a when and only when the switch operating apparatus occupies its extreme normal position, and 40 that, the notch 36^b in the rack bar 6^b will align with the locking dog 35^b when and only when the switch operating apparatus occupies its extreme reverse position. The parts are further so proportioned that the lock operating lever 33^a will 45 be rotated to a locking position in which the locking dog 35^a will enter the notch 36^a, or to an unlocking position in which the locking dog 35^a is withdrawn from the notch 36^a, according as 50 the piston 29^a occupies its retracted or its projected position, and that, the lock operating lever 33^b will be rotated to a locking position in which the locking dog 35^b will enter the notch 36^b, or to an unlocking position in which the locking dog 55 70 75 35^b is withdrawn from the notch 36^b, according

as the piston 29^b occupies its retracted or its projected position. The lock operating levers are constantly biased to their locking positions by means of springs 37^a and 37^b which surround the piston rods 30^a and 30^b between the end wall 5 32 of the compartment 28 and collars 38^a and 38^b which are provided on the piston rods.

The lock operating levers 33^a and 33^b control a circuit controller E for indicating whether the switch operating apparatus is locked in its normal or its reverse position, or is unlocked. As here shown, this circuit controller comprises two movable contact fingers 39^a and 40^a which are operatively connected with the lock operating lever 33^a, and two other movable contact fingers 15 39^b and 40^b which are operatively connected with the lock operating lever 33^b. The finger 39^a cooperates with two fixed contact members 41^a and 42^a to close a contact 39^a—41^a or 39^a—42^a according as the lever 33^a occupies its locking or 20 its unlocking position; the finger 40^a cooperates with a fixed contact member 43^a to close a contact 40^a—43^a when and only when the lever 33^a occupies its unlocking position; the finger 39^b cooperates with two fixed contact members 41^b and 42^b to close a contact 39^b—41^b or 39^b—42^b according as the lever 33^b occupies its locking or 25 its unlocking position; and the finger 40^b cooperates with a fixed contact member 43^b to close a contact 40^b—43^b when and only when the lever 33^b occupies its unlocking position.

The cylinders 27^a and 27^b are arranged to be supplied with fluid pressure through passageways 45^a and 45^b which are formed in the cylinder head 4, and which communicate with pipes 46^a and 46^b 30 through valves 47^a and 47^b. When the valves 47^a and 47^b occupy their normal or open positions in which they are shown in Fig. 1, communication is established between the pipes 46^a and 46^b and the interiors of the cylinders 27^a and 27^b, but 35 when the valves 47^a and 47^b are rotated from the positions shown through a sufficient angle in a counterclockwise direction to their reverse or closed positions, the cylinders 27^a and 27^b are then disconnected from the pipes 46^a and 46^b 40 and are connected with atmosphere through suitable vent ports, only one of which 48^a is shown in the drawings. To facilitate rotation of the valves 47^a and 47^b between their open and closed positions, these valves are connected together by 45 means of a connecting member 49 which is formed with sockets at its opposite ends for engagement with the squared confronting ends 50^a and 50^b of the valves 47^a and 47^b and which is also formed with another socket 51 for the reception of a removable operating lever. This operating lever may be of any suitable type, but will usually comprise the handle of a hand crank which is provided for the purpose of enabling the switch operating apparatus to be manually operated between its two extreme positions, one such hand crank and the method of operably connecting it with the switch operating apparatus being shown in the previously referred to Coleman Patent No. 1,791,799. The member 49 is further formed with 55 a depending portion 52 which cooperates with two auxiliary operating rods 53^a and 53^b which are slidably supported adjacent their outer ends in suitable guide lugs 54 formed on the undersides of the cylinders 27^a and 27^b, and which are secured at their inner ends to the piston rods 30^a and 30^b, respectively, the parts being so proportioned that, when the valves are moved to their closed positions by rotation of the member 49 to 60 permit manual operation of the switch operating 65 apparatus being shown in the previously referred to Coleman Patent No. 1,791,799. The member 49 is further formed with a depending portion 52 which cooperates with two auxiliary operating rods 53^a and 53^b which are slidably supported adjacent their outer ends in suitable guide lugs 54 formed on the undersides of the cylinders 27^a and 27^b, and which are secured at their inner ends to the piston rods 30^a and 30^b, respectively, the parts being so proportioned that, when the valves are moved to their closed positions by rotation of the member 49 to 65 permit manual operation of the switch operating 70 apparatus being shown in the previously referred to Coleman Patent No. 1,791,799. The member 49 is further formed with a depending portion 52 which cooperates with two auxiliary operating rods 53^a and 53^b which are slidably supported adjacent their outer ends in suitable guide lugs 54 formed on the undersides of the cylinders 27^a and 27^b, and which are secured at their inner ends to the piston rods 30^a and 30^b, respectively, the parts being so proportioned that, when the valves are moved to their closed positions by rotation of the member 49 to 75 permit manual operation of the switch operating 75

apparatus, the depending portion 52 will engage the rod 53^a or 53^b according as the switch operating apparatus then occupies its extreme normal or its extreme reverse position, and will rotate the lock operating lever 33^a or 33^b, as the case may be, from its locking to its unlocking position. It will be seen, therefore, that operation of the valves to their closed positions to permit the operation of the switch movement by hand will 10 automatically unlock the switch movement if the switch movement is then locked in either of its extreme positions.

During normal operation of the apparatus, fluid is selectively supplied to the pipes 46^a and 46^b by means of an electropneumatically operated switch valve mechanism CP. This valve mechanism may be of any suitable type but, as here shown, this valve mechanism is similar to that described and claimed in Letters Patent of the 15 United States No. 1,875,853, granted to J. P. Coleman, on September 6, 1932, for Railway traffic controlling apparatus. Since this valve mechanism is described in detail in the said United States Patent No. 1,875,853, it is believed to be 20 sufficient for purposes of the present disclosure to state that this valve mechanism is provided with the usual normal magnet N¹, reverse magnet R¹, and lock magnet L¹, it being understood that, when the normal and lock magnets are both energized, fluid will be admitted to the pipe 46^b, whereas, when the reverse and lock magnets are both energized, fluid will be admitted to the pipe 46^a. The valve mechanism CP is also provided with normal contacts 54—54^b and 55—55^b which 25 become closed when the normal and lock magnets both become energized, and which subsequently remain closed until the reverse and lock magnets both become energized, and with reverse contacts 54—54^a and 55—55^a which become closed 30 when the reverse and lock magnets both become energized and which remain closed until the normal and lock magnets subsequently become energized.

The magnet valves R¹, and L¹, and N¹ are controlled in part by a manually operable lever A which in the form here shown is movable between a normal position N, a normal indication position B, a reverse indication position D, and a reverse position R. Operatively connected with the lever A are four contacts 56, 57, 58, and 59, the two contacts 56 and 58 being closed when the lever occupies its normal position N, its normal indicating position B, or any position intermediate these two positions; and the remaining two contacts 57 and 59 being closed when the lever occupies its reverse position R, its reverse indicating position D, or any position intermediate these two positions.

The magnet valves R¹, L¹, and N¹ are also controlled in part by the circuit controller E, and in part by a polarized indication relay K, which relay, in turn, may, if desired, be used to govern the movements of the lever A. The means for governing the movements of the lever A by the relay K are not shown in the drawings because these means form no part of our present invention, but these means may, for example, be similar to those shown in an application for Letters Patent of the United States Serial No. 406,883, filed by B. E. O'Hagan, on November 13, 1929, for Railway switch operating apparatus.

Relay K is controlled by the circuit controllers C and E and by the contacts of the switch valve mechanism CP.

As shown in the drawings, the switch S, the

switch operating apparatus, and the lever A all occupy their normal positions. Under these conditions, a normal indicating circuit for relay K is closed, and current of normal polarity flows from terminal X of a suitable source of current not 5 shown in the drawings through wire 60, contact 54—54^b of switch valve mechanism CP, wire 61, contact 21^a—22^a of circuit controller C, wire 62, contact 39^a—41^a of circuit controller E, wire 63, the winding of relay K, wires 64 and 60, contact 10 24^a—25^a of circuit controller C, and wire 65 to terminal O of the source. Relay K is therefore energized in its normal direction, so that its neutral back contacts are open and its normal polar contacts are closed. All circuits for the 15 magnets R¹, L¹, and N¹ of the valve mechanism CP are open, and these magnets are therefore all deenergized.

We will now assume that the operator desires to reverse switch S. To do this, he will first 20 move lever A from its normal position N to its reverse indicating position D, thus opening contacts 56 and 58 of this lever, and closing contacts 57 and 59. The closing of contact 57 completes a circuit for the reverse magnet R¹ of valve 25 CP, while the closing of contact 59 completes a circuit for the lock magnet L¹. The circuit for the reverse magnet R¹ passes from terminal X through wires 66 and 67, contact 57 of lever A, wire 68, contact 40^b—43^b of circuit controller E, 30 wire 69, the winding of magnet R¹, and wires 70 and 71 to terminal O. The circuit for the lock magnet L¹ passes from terminal X through contact 59 of lever A, wire 72, normal polar contact 73 of relay K, wires 74, 75, and 76, the winding of 35 lock magnet L¹ of valve mechanism CP, and wire 77 to terminal O. The magnets R¹ and L¹ therefore become energized and, as was previously pointed out, the energization of these magnets causes the contacts 54—54^b and 55—55^b of switch 40 valve CP to become opened and contacts 54—54^a and 55—55^a to become closed. The opening of contact 54—54^b of valve mechanism CP interrupts the circuit that was previously closed for relay K, while the closing of contact 54—54^a completes 45 a short circuit for this magnet which may be traced from the left-hand terminal of relay K through wires 64 and 78, contact 54—54^a of valve mechanism CP, wire 61, contact 21^a—22^a of circuit controller C, wire 62, contact 39^a—41^a of circuit controller E, and wire 63 to the other terminal of relay K. Relay K therefore becomes 50 deenergized and closes its back contact 77. The closing of contact 77 completes another energizing circuit for magnet valve L¹ which latter circuit may be traced from terminal X through back contact 77 of relay K, wire 76, the winding of magnet L¹, and wire 71 to terminal O. The energization of magnets R¹ and L¹ of valve mechanism CP also causes fluid pressure to be admitted 55 to the auxiliary cylinder 27^a of the switch operating apparatus, and the fluid thus admitted to this cylinder moves piston 29^a from its retracted to its projected position, thereby actuating the lever 32^a to unlock the switch, and at the same time 60 causing contact 39^a—41^a of circuit controller E to become opened and contacts 39^a—42^a and 40^a—43^a of circuit controller E to become closed. The closing of contact 39^a—42^a of circuit controller E completes a shunt circuit for the winding of relay K, which shunt circuit insures that 65 this relay will become deenergized and will remain deenergized while the switch is being reversed if this relay has not already become deenergized, and which circuit may be traced 70 75

from the left-hand terminal of relay K through wire 78, contact 39^b—42^b of circuit controller E, wire 79, contact 39^a—42^a of circuit controller E, and wire 63 to the other terminal of the winding 5 of relay K. The movement of piston 29^a to its projected position, in addition to unlocking the switch, also uncovers port 16^a, thus admitting fluid pressure to cylinder 2^a, and hence causing the switch operating apparatus to move from its 10 normal position to its reverse position in the manner previously described. As soon as the switch operating apparatus starts to move to its reverse position and before the locking plunger 15^b becomes disengaged from the lock rod L to 15 unlock the switch S, the roller 19^a carried by the lever 18^a of circuit controller C is forced out of the notch 17^a in the cam member 17, whereupon contacts 21^a—22^a and 24^a—25^a of circuit controller C become opened and contacts 21^a—23^a 20 and 24^a—26^a become closed. The operation of these contacts of circuit controller C, under these conditions, however, has no immediate effect on the remainder of the apparatus unless the contact 39^a—41^a of circuit controller E failed to open 25 for any reason in response to the unlocking movement of lever 33^a, in which event another shunt circuit for relay K would then become closed which latter circuit may be traced from the left-hand terminal of relay K through wires 30 64 and 80, contact 24^a—26^a of circuit controller C, wire 83, contact 21^b—23^b of circuit controller C, wire 62, contact 39^a—41^a of circuit controller E, and wire 63 to the other terminal of relay K. The function of this latter circuit is to insure 35 that relay K will become deenergized in the case of a failure of the type described, and thus prevent a dangerous condition due to this failure. When the switch reaches its full reverse position, the notch 17^a in the cam member 17 moves into 40 alignment with the roller 19^b carried by the lever 18^b, and spring 20 then operates lever 18^b from the position shown to the position in which the roller 19^b enters the notch 17^a, thus opening contacts 21^b—23^b and 24^b—26^b of circuit controller 45 C, and closing contacts 21^b—22^b and 24^b—25^b of this circuit controller. Furthermore, notch 36^b in the rack bar 6^b moves into alignment with locking dog 35^b, and spring 37^b then moves lever 33^b to its locking position, thus causing contacts 50 39^b—42^b and 40^b—43^b of circuit controller E to become opened, and contact 39^b—41^b of circuit controller E to become closed. The opening of contact 39^b—42^b interrupts the short circuit which was previously closed for relay K at this 55 contact, while the closing of contact 39^b—41^b completes a reverse energizing circuit for relay K passing from terminal X through contact 24^b—25^b of circuit controller C, wires 80 and 64, the winding of relay K, wire 63, contact 39^a—42^a of circuit controller E, wire 79, contact 39^b—41^b of circuit controller E, wires 81 and 62, contact 21^b—22^b of circuit controller C, wire 84, contact 55—55^a of switch valve mechanism CP, and wire 85 to terminal O. The current supplied to relay 60 K over this circuit is of reverse polarity and this relay therefore now reverses its polar contacts and opens its back contact 77. When back contact 77 of relay K becomes opened, all circuits which were previously closed for lock magnet L¹ 65 are interrupted and this magnet therefore now becomes deenergized. Furthermore, the opening of contact 40^b—43^b of circuit controller E interrupts the circuit which was previously closed for magnet R¹, and magnet R¹ therefore also becomes deenergized. The deenergization of mag-

nets L¹ and R¹ cuts off the supply of fluid pressure to cylinders 27^a and 2^a and permits the fluid which was previously supplied to these cylinders to escape to atmosphere. The energization of relay K in its reverse direction also acts to permit 5 lever A to be moved from its reverse indicating position to its full reverse position in a manner which is described in the previously referred to O'Hagan patent, and when this lever has been moved to its reverse indicating position, all parts 10 are then in their proper reverse positions.

We will assume that the switch has been moved to its reverse position in the manner just described, and that the operator wishing to restore the switch to its normal position moves 15 lever A to its normal indicating position. This movement of the lever completes a circuit for the normal magnet N¹ passing from terminal X through wires 66 and 67, contact 56 of lever A, wire 183, contact 40^a—43^a of circuit controller 20 E, wire 184, and the winding of magnet N¹ to terminal O. This movement of the lever also completes a circuit for the lock magnet L¹ passing from terminal X through wire 66, contact 58 of lever A, wire 185, reverse polar contact 86 25 25 of relay K, wires 87, 75, and 76, winding of magnet L¹, and wire 71 to terminal O. The lock magnets L¹ and N¹ therefore both become energized, and cause the contacts of this valve mechanism to be restored to the positions in which they 30 are shown in the drawings. The resultant opening of contact 55—55^a of valve mechanism CP 35 interrupts the reverse indication circuit which was previously closed for relay K, and completes a shunt circuit for this relay, which latter circuit may be traced from the left-hand terminal of relay K through wires 64 and 78, contact 55—55^b of valve mechanism CP, wire 84, contact 21^b—22^b of circuit controller C, wire 62, contact 39^b—41^b of circuit controller E, wire 79, contact 39^a—42^a of circuit controller E, and wire 63 to the 40 other terminal of relay K. Relay K therefore now becomes deenergized and closes the previously traced auxiliary circuit for the lock magnet L¹ at contact 77. The energization of the magnets L¹ and N¹ also causes fluid pressure to be 45 admitted to the cylinder 27^b through the pipe 46^b and port 45^b, and this fluid pressure forces piston 29^b to the position in which the locking dog 35^b becomes withdrawn from the notch 36^b, 50 thereby opening contact 39^b—41^b, and closing contacts 39^b—42^b and 40^b—43^b of circuit controller E. The opening of contact 39^b—41^b of circuit controller E interrupts the shunt circuit for relay K which was previously closed at this 55 contact, while the closing of contact 39^b—42^b of circuit controller E completes another shunt circuit for relay K which latter circuit may be traced from the left-hand terminal of relay K through wire 78, contact 39^b—42^b of circuit controller E, wire 79, contact 39^a—42^a of circuit controller E, and wire 63 to the other terminal of relay K. The movement of piston 29^b to its projected position also uncovers ports 16^b and, since the switch operating apparatus is then unlocked, the 65 fluid pressure thus admitted to cylinder 27^b causes the switch operating apparatus to move from its reverse position to its normal position, and thus move switch S from its reverse position to its normal position. As soon as the switch operating apparatus starts to move toward its normal position, contacts 21^b—22^b and 24^b—25^b 70 of circuit controller C become opened, and contacts 21^b—23^b and 24^b—26^b of circuit controller C become closed in a manner which will be readily 75

understood from an inspection of the drawings. The operation of these contacts under these conditions, however, has no immediate effect on the remainder of the apparatus unless contact 5 39^b—41^b had failed to open in response to the unlocking movement of lever 33^b in which event the closing of contact 24^b—26^b would complete another short circuit for relay K passing from the left-hand terminal of the relay through wires 10 64 and 80, contact 24^b—26^b of circuit controller C, contact 21^a—23^a of circuit controller C, wire 62, contact 39^b—41^b of circuit controller E, wire 79, contact 39^a—42^a of circuit controller E, and wire 63 to the other terminal of relay K. When 15 the switch reaches its full normal position, circuit controller C will then open its contacts 21^a—23^a and 24^a—26^a and will close its contacts 21^a—22^a and 24^a—25^a. Furthermore, the spring 37^a will cause the locking plunger 35^a to enter the 20 notch 36^a in the rack bar 6^a, and will thus cause the switch operating apparatus to become locked in its normal position. The movement of the locking plunger 35^a to its locking position will cause contacts 39^a—42^a and 40^a—43^a of circuit controller E to become opened, and contact 25 39^a—41^a of circuit controller E to become closed. The opening of contact 40^a—43^a will interrupt the circuit which was previously closed for the normal magnet N¹, thus causing this magnet to be 30 come deenergized, and to cut off the supply of fluid pressure to the cylinder 27^b. The opening of contact 39^a—42^a of circuit controller E will interrupt the shunt circuit which was previously closed for relay K, and the closing of contact 35 39^a—41^a of circuit controller E will complete the previously traced normal energizing circuit for relay K. Relay K will therefore become energized in its normal direction, thus causing its back contact 77 to open and its polar contacts to 40 move from their reverse positions to their normal positions. When the back contact 77 of relay K becomes opened, the lock magnet L¹ will become deenergized, and all of the lock magnets will then be deenergized so that the supply of fluid pressure to cylinders 27^b and 2^b will be 45 cut off, and these cylinders will both be vented to atmosphere. The energization of relay K will permit the lever A to be moved from its normal indicating position to its full normal position and, when the lever is moved to its normal position, 50 all parts will then be restored to the positions in which they are shown in the drawings.

It should be pointed out that, with the apparatus constructed in the manner described since the apparatus is firmly locked in both its normal and reverse positions, any danger of the apparatus creeping due to vibration or the like is prevented. This is desirable because it permits all of the magnets of the valve CP to be deenergized 55 except while the switch is being reversed from one position to the other, thereby effecting a marked saving in energy.

It should also be pointed out that, with the apparatus constructed in the manner described if, when the switch is reversed, it fails to reach the extreme position toward which it is being moved for any reason, the locking plunger 35, which would have entered the associated notch 36 if the movement of the switch had been completed, will be prevented from moving to its locking position and, under these conditions, the contacts of the circuit controller E, which would have been closed by the movement of the locking plunger to its locking position, will remain open 70 and relay K will remain deenergized. As a re-

sult, the operator may immediately restore the lever to the position from which it was moved to reverse the switch and, when he does this, the switch will be restored to its original position, thus insuring that the operator will not lose 5 control of the switch.

Referring now to Fig. 4, we have here shown a modified form of valve mechanism CP¹ which may be used in place of the valve mechanism CP shown in Fig. 1 for controlling the supply of 10 fluid pressure to the cylinders 27^a and 27^b, together with suitable control circuits for controlling this modified form of valve mechanism. As here illustrated, this valve mechanism comprises a slide valve 90 which is mounted in a 15 valve chamber 91 formed in the cylinder head 4 adjacent the outer ends of the cylinders 27^a and 27^b. The slide valve 90 is biased by means of a spring assembly F to an intermediate position in which it is shown in the drawings, and is arranged 20 to be moved from its intermediate position to a lower or normal position or an upper or reverse position by means of a polarized control magnet P. The centering spring assembly may be of any suitable type, but in the form here shown, this 25 assembly comprises a fixed cylindrical housing 93 provided at its opposite ends with end plates 94 having formed therein axially aligned openings 95 through which a valve operating rod 96 extends with some clearance. Pinned to the rod 30 96 within the openings 95 are collars 97, and surrounding the rod between stop washers 98 which are slidably mounted on the rod 96 adjacent the collars 97 is a compressed coil spring 99 which constantly biases the washers to the 35 position in which they engage the associated collars and the inner sides of the end plates 94, the parts being so proportioned that, when the stop washers are engaging both the end plates and the collars, the valve assembly will be held 40 in its intermediate position.

The polarized magnet P comprises a magnetizable core 101, a permanently magnetized core 102, and a magnetizable core 103 connected together at one end by a backstrap 104, the two magnetizable cores 101 and 103 being disposed on opposite sides of the constantly magnetized core 102 and being provided with energizing windings 105 and 106, respectively. Pivotaly attached to the permanently magnetized core 102 45 at the end opposite to the backstrap 104 is an 50 armature 107 which is arranged to swing toward the core 103 or the core 101 according as the windings 105 and 106 are supplied with current 55 of normal or reverse polarity. The armature 107 is formed with an integral arm 108 which is 60 pivotally connected with the free end of the operating rod 96 in such manner that the slide valve will be moved to its normal or its reverse position according as the armature is swung toward the magnetizable core 103 or the magnetizable core 101.

The valve chamber 91 communicates with the cylinders 27^a and 27^b through two ports 109^a and 109^b, respectively, and with a fluid pressure supply pipe 110 through two ports 111^a and 111^b which are formed in the outer wall of the valve chamber, and which align axially with the ports 109^a and 109^b, respectively. The valve chamber 91 also communicates at its upper and lower ends 70 with atmosphere through two ports 112^a and 112^b. The slide valve 90 is provided with four passageways 113^a, 114^a, 113^b, and 114^b. The passageway 113^a is so arranged that, when the slide valve occupies its intermediate position in 75

which it is shown in the drawings or its normal position, this passageway will align with the port 109^a, and will thus establish communication between the cylinder 27^a and the outer atmosphere 5 through the port 109^a, the passageway 113^a, the upper end of the valve chamber 91, and the port 112^a; and the passageway 113^b is so arranged that when the slide valve occupies its intermediate position or its reverse position, this passageway 10 will align with the port 109^b to establish communication between the cylinder 27^b and the outer atmosphere through the port 109^b, the passageway 113^b, the lower end of the valve chamber 91, and the port 112^b. The passageway 15 114^b is so arranged that, when the slide valve occupies its lower or normal position, this passageway will align with the ports 109^b and 111^b to connect the cylinder 27^b with the pipe 110, and the passageway 114^a is so arranged that, 20 when the slide valve occupies its reverse position, this passageway will align with the ports 109^a and 111^a, and will thus connect the cylinder 27^a with the pipe 110.

The valve mechanism CP¹ also comprises a 25 movable contact finger 115 which is operatively connected with the operating rod 96, and which cooperates with three fixed contact members 116, 117, or 118 to close a contact 115-116, a contact 115-117, or a contact 115-118 according as the 30 slide valve 90 occupies its intermediate, its reverse, or its normal extreme position.

The remainder of the apparatus shown in Fig. 4 is similar in all respects to the corresponding apparatus shown in Fig. 1.

35 The operation as a whole of the apparatus shown in Fig. 4 is as follows: As illustrated in the drawings, all parts are in their normal positions. Under these conditions, all circuits for the polarized control relay P are open, and this relay is therefore deenergized. The polarized indication relay K, however, is energized by virtue of a normal indication circuit which passes from terminal X of the source through wire 120, contact 21^a-22^a of circuit controller C, wire 62, contact 39^a-41^a of circuit controller E, wire 121, 40 contact 115-116 of valve mechanism CP¹, wire 122, the winding of relay K, wires 64 and 124, contact 24^a-25^a of circuit controller C and wire 125 to terminal O.

We will now assume that the operator, wishing 50 to reverse the switch S, moves the lever A from its normal position N to its reverse indicating position D. This movement of the lever completes the reverse control circuit for the control magnet P, and current of reverse polarity flows from terminal X through contact 51 of lever A, wires 126 and 127, the windings 105 and 106 of magnet P in series, wires 128 and 129, contact 40^b-43^b of circuit controller E, an asymmetric unit 130 in its low resistance direction, wire 131, and contact 59 of lever A to terminal O. The current thus supplied to the control magnet P causes the armature of the magnet to swing toward the core 101, and this movement of the armature causes contact 115-116 of the valve mechanism CP¹ to open and contact 115-117 to close. The opening of the contact 115-116 of the valve mechanism CP¹ interrupts the normal energizing circuit that was previously closed for relay K, while the closing of contact 115-117 completes a short circuit for this relay which latter circuit may be traced from the right-hand terminal of relay K through wires 64, 135, and 132, contact 115-117 of valve mechanism CP¹, and wire 122 to the other terminal of relay K. Relay K, therefore, be-

comes deenergized for obvious reasons. The movement of armature 107 toward core 101 of the control magnet P also moves the slide valve 90 to its upper or reverse position, thereby disconnecting the cylinder 27^a from atmosphere and connecting this cylinder with the source of fluid pressure. As a result, fluid pressure is now admitted to the cylinder 27^a and this pressure causes the piston 29^a to move from its retracted to its projected position, thereby unlocking the 10 switch operating apparatus and at the same time causing contact 39^a-41^a of circuit controller E to become opened and contacts 39^a-42^a and 40^a-43^a of circuit controller E to become closed. The operation of the contacts of circuit controller 15 E under these conditions, however, has no effect on the apparatus unless the contact 115-116 of the polarized control magnet P has failed to open in the usual manner when this magnet became energized, in which event the closing of contact 39^a-42^a will complete another shunt circuit for relay K which latter circuit may be traced from the right-hand terminal of relay K through wires 64, 135, and 136, contact 39^b-42^b of circuit controller E, wire 137, contact 39^a-42^a of circuit controller E, wire 121, contact 115-116 of valve mechanism CP¹, and wire 122 to the other terminal of relay K. It should be noted that, when this circuit becomes closed, relay K will, of course, become deenergized. The movement of 20 piston 29^a to its projected position also uncovers port 16^a thus admitting fluid pressure to cylinder 2^a, and hence causing the switch operating apparatus to reverse in the manner previously described in connection with Fig. 1. As soon as the 25 switch operating apparatus starts to move, contacts 21^a-22^a and 24^a-25^a of circuit controller C become opened and contacts 21^a-23^a and 24^a-26^a become closed. The closing of contacts 24^a-26^a and 21^a-23^a has no immediate effect on 30 the remainder of the apparatus if the contacts of the switch valve mechanism CP¹ have functioned in the proper manner in response to the energization of the control relay P and the circuit controller E has functioned in the proper manner in response to the unlocking movement of the bell crank lever 33^a. If, however, the contacts of the valve mechanism CP¹ have failed to function in the proper manner so that contact 115-116 is 35 still closed and the contacts of the circuit controller E have also failed to function so that the contact 39^a-41^a is closed, then the closing of the contacts 24^a-26^a and 21^a-23^a complete another shunt circuit for relay K which may be traced from the right-hand terminal of relay K, wires 40 64 and 124, through contact 24^a-26^a of the circuit controller C, wire 133, contact 21^b-23^b of circuit controller C, wires 83 and 62, contact 39^a-41^a of circuit controller E, wire 121, contact 115-116 of valve mechanism CP¹, and wire 122 to 45 relay K. The closing of this latter circuit will, of course, cause relay K to become deenergized if this relay has not already become deenergized. When the switch operating apparatus reaches its full reverse position, the roller 19^b will enter the 50 notch 17^a in the cam 17 and will thus cause contacts 24^b-26^b and 21^b-23^b of circuit controller C to open and contacts 24^b-25^b and 21^b-22^b of circuit controller C to become closed. Furthermore, the spring 37^b will cause the locking plunger 55 35^b to enter the notch 36^b in the rack bar 6^b, thus locking the switch in its reverse position, and will also cause contacts 39^b-42^b and 40^b-43^b of circuit controller E to open and contact 39^b-41^b of circuit controller E to become closed. The 60 70 75

opening of contact 40^b—43^b will interrupt the circuit over which the control magnet P was previously energized, and this magnet will therefore now become deenergized and will permit the 5 spring mechanism F to restore the slide valve 90 to its intermediate position. When the slide valve reaches its intermediate position, it will cut off the further supply of fluid to the cylinders 27^a and 2^a and will permit the fluid which was 10 previously supplied to these cylinders to escape to atmosphere. When contact 39^b—41^b of circuit controller E and contacts 24^b—25^b and 21^b—22^b of circuit controller C are all closed, a reverse indication circuit for relay K is completed 15 and current flows from terminal X through contact 24^b—25^b of circuit controller C, wires 80, 124, and 64, the winding of relay K, wire 122, contact 115—116 of valve mechanism CP¹, wire 121, contact 39^a—42^a of circuit controller E, wire 131, 20 contact 39^b—41^b of circuit controller E, wires 139, 62, and 83, contact 21^b—22^b of circuit controller C, and wire 140 to terminal O. The current supplied to relay K over this reverse control circuit 25 is of reverse polarity and this relay, therefore, picks up its neutral armature and reverses its polar contacts. When relay K picks up its neutral armature and reverses its polar contacts, the control mechanism for controlling the lever A by the relay K becomes operated, and permits 30 movement of the lever from its reverse indicating position to its full reverse position. When the lever reaches this full reverse position, all parts then occupy their proper reverse positions.

We will now assume that the parts have been 35 moved to their reverse positions in the manner just described and that the operator wishing to restore the switch to its normal position moves the lever to its normal indicating position. This movement of the lever completes a normal control circuit for the control relay P, and current of normal polarity flows over this circuit from terminal X through contact 56 of lever A, wires 141 and 131, an asymmetric unit 142 in its low resistance direction, contact 40^a—43^a of circuit controller E, wires 143 and 128, the windings 105 and 106 of the control magnet P, wire 127, and contact 58 of lever A to terminal O. The control magnet P, therefore, now swings its armature toward the pole piece 103 thus causing contact 50 115—116 of valve mechanism CP¹ to become opened and contact 115—118 to become closed. The opening of contact 115—116 interrupts the reverse energizing circuit for the indication relay K, while the closing of contact 115—118 completes 55 a shunt circuit for this relay which is similar to that previously traced when the armature of magnet P swung toward core 101 with the exception that this latter circuit includes contact 115—118 of the valve mechanism CP¹ in place of the contact 115—117 of this valve mechanism. The movement of the armature 107 toward the core 103 also causes the slide valve 90 to move downwardly to its normal position, thereby causing fluid pressure to be admitted to 60 auxiliary cylinder 27^b. The fluid thus admitted to this cylinder moves the locking plunger 35^b from its locking to its unlocking position and causes contact 39^b—41^b of circuit controller E to become opened and contacts 39^b—42^b and 40^b—43^b to become closed. The opening of contact 39^b—41^b interrupts the reverse indication circuit for relay K at this contact but, if the contacts controlled by the switch valve mechanism CP¹ have functioned properly, this circuit 65 70 75 is already open and the opening of this contact

under those conditions has no effect on the apparatus. The closing of contact 39^b—42^b of circuit controller E likewise has no immediate effect on the apparatus if the contacts of the switch valve mechanism CP¹ occupy their proper positions but, if contact 115—116 of this valve mechanism is still closed for any reason, then the closing of contact 39^b—42^b completes another shunt circuit for relay K which may be traced from the right-hand terminal of relay K through wires 10 64, 135, and 136, contact 39^b—42^b of circuit controller E, wire 137, contact 39^a—42^a of circuit controller E, wire 121, contact 115—116 of valve mechanism CP¹, and wire 122 to the other terminal of relay K. It should be noted that the 15 function of this latter circuit is to insure that relay K will become deenergized in the event of a failure of the contacts of the switch valve mechanism CP¹ to function in the proper manner. The movement of the piston 29^b to its projected position to unlock the switch operating apparatus uncovers the port 16^b and permits fluid pressure to be supplied to the cylinder 2^b. This fluid pressure will cause the switch operating apparatus to move the switch from its reverse position to its normal position. As soon as the switch operating apparatus starts to move, contacts 21^b—22^b and 24^b—25^b of circuit controller C will become opened, and contacts 21^b—23^b and 24^b—26^b will become closed. This 20 operation of the contacts of circuit controller C will have no immediate effect on the remainder of the apparatus unless both the contacts of the valve mechanism CP¹ and the contacts of the circuit controller E have failed to function in the 25 proper manner in which event another shunt circuit for relay K will be closed, which latter circuit may be traced from the right-hand terminal of relay K through wires 64, 124, and 80, contact 24^b—26^b of circuit controller C, wire 144, 40 contact 21^a—23^a of circuit controller C, wires 62 and 139, contact 39^b—41^b of circuit controller E, wire 137, contact 39^a—42^a of circuit controller E, wire 121, contact 115—116 of switch valve mechanism CP¹, and wire 122 back to the other terminal of relay K. The function of this latter circuit is, of course, to insure that relay K will become deenergized in the event that this relay has not become previously deenergized due to the operation of the contacts of the switch valve mechanism and of the circuit controller E. When the switch reaches its full normal position, contacts 21^a—23^a and 24^a—26^a of circuit controller C will become opened and contacts 24^a—25^a and 21^a—22^a will become closed. Furthermore, the 45 locking plunger 35^a will enter the notch 36^a in the rack bar 6^a to lock the switch in its normal position and the contacts 39^a—42^a and 40^a—43^a of circuit controller E will become opened and the contact 39^a—41^a of circuit controller E will 50 become closed. The opening of contact 40^a—43^a of circuit controller C will deenergize the control magnet P and, when this magnet becomes deenergized, the supply of fluid pressure to cylinders 27^b and 2^b will be cut off, and the fluid 55 which was previously supplied to these cylinders will be vented to atmosphere. Furthermore, contact 115—118 of the valve mechanism CP¹ will become open and contact 115—116 will become closed. When this contact becomes closed, the 60 previously traced normal energizing circuit for indication relay K will then become closed, and this relay will therefore close its front contacts and its normal polar contacts. When this happens, the mechanism controlled by this relay for 65 70 75

controlling lever A will be actuated to permit the lever to be moved from its normal indication position to its full normal position. When the lever reaches its full normal position, all parts will then be restored to their normal positions in which they are shown in the drawings.

It should be pointed out that, when the apparatus occupies either its normal or its reverse position if a maintainer operates the contacts 10 of the valve mechanism CP¹ in a manner to cause the contact 115-116 to open and either contact 115-117 or 115-118 to become closed, this operation will cause the indication relay to become deenergized, and will immediately connect 15 this relay in one or the other of the shunt circuits previously traced for this relay. Likewise, if any of the contacts of either circuit controller C or circuit controller E are inadvertently operated from the positions corresponding to the 20 position which the switch then occupies when the switch is in either of its extreme positions, the indication circuit which was previously closed for relay K will become interrupted and one or the other of the previously traced shunt circuits 25 controlled by the circuit controllers C and E will become closed, and will cause relay K to immediately become deenergized. In actual practice, relay K will usually be used not only to control lever A, but also to control the circuits for the 30 signals governing traffic over switch S in such manner that these signals will occupy their stop positions unless relay K is energized, and it will be apparent, therefore, that with apparatus embodying our invention every precaution has been 35 taken to prevent an unsafe condition from happening.

One advantage of apparatus embodying our invention is that no electrical energy is supplied to the valve control mechanism when the switch 40 occupies either of its extreme positions, and as a result a marked saving in energy is effected.

Another advantage of apparatus embodying our invention is that, since the switch operating apparatus is locked, when it occupies either extreme position, by means of the locking plungers 45 35^a and 35^b in the manner previously described, the possibility of the apparatus creeping due to vibration and the like is prevented.

Although we have herein shown and described 50 only two forms of apparatus embodying our invention, it is understood that various changes and modifications may be made therein within the scope of the appended claims without departing from the spirit and scope of our invention.

Having thus described our invention, what we claim is:

1. Railway switch operating apparatus comprising a housing containing a pair of drive cylinders containing pistons operatively connected with the switch, a dog for each said piston for locking the piston, said dogs being biased to locking positions, a pair of auxiliary cylinders located in said housing, a piston in each auxiliary cylinder for moving one of said dogs from its locking to an unlocking position and for controlling the supply of fluid pressure to an associated one of said drive cylinders, two manually operable valves one for controlling the supply of fluid pressure 70 to each auxiliary cylinder, and means effective when either of said valves is moved to its closed position for moving the associated dog to its unlocking position if it then occupies its locking position.

2. Railway switch operating apparatus com-

prising a housing containing a pair of spaced drive cylinders containing pistons operatively connected with the switch, a dog for each said piston for locking the piston, a pair of auxiliary cylinders located in said housing and positioned 5 between said drive cylinders, a piston in each drive cylinder operatively connected with an associated one of said dogs for moving such dog to an unlocking position and to admit fluid pressure to an associated one of said drive cylinders, a 10 pair of valves one for controlling the supply of fluid pressure to each of said auxiliary cylinders and each having an open and a closed position, a member connecting said valves for jointly moving said valves to their closed positions, and 15 means controlled by said member and effective when said valves are moved to their closed positions by said member for moving either of said dogs to its unlocking position if it then occupies its locking position.

3. Railway switch operating apparatus comprising a housing containing a pair of spaced drive cylinders containing pistons operatively connected with the switch for moving the switch 20 between its two extreme positions, a dog for each said piston for locking the piston, a pair of auxiliary cylinders in said housing, a piston in each auxiliary cylinder for governing one of said dogs and for controlling the supply of fluid pressure to the associated drive cylinder, a manually 25 operable lever, an indication relay, means controlled by said lever and by said relay for controlling the supply of fluid to said auxiliary cylinders, and means controlled by said dogs for controlling said indication relay.

4. Railway switch operating apparatus comprising a housing containing a pair of spaced drive cylinders containing pistons operatively connected with the switch for moving the switch 40 between its two extreme positions, a dog for each said piston for locking the piston, a pair of auxiliary cylinders in said housing, a piston in each auxiliary cylinder for governing one of said dogs and for controlling the supply of fluid pressure to the associated drive cylinder, a manually 45 operable lever, an indication relay, means controlled by said lever and by said relay for controlling the supply of fluid to said auxiliary cylinders, means for normally energizing said relay when the switch is moved to either extreme position, and means controlled by said dogs for preventing said relay from becoming energized unless one or the other of said first mentioned pistons is locked by the associated dog.

5. Railway switch operating apparatus comprising a housing containing a pair of spaced drive cylinders containing pistons operatively connected with the switch, lock mechanism for locking said pistons against movement in their extreme positions, a pair of auxiliary cylinders 60 in said housing containing pistons for actuating said lock mechanism and for controlling the supply of fluid pressure to said drive cylinders, a polarized control magnet, valve mechanism operated by said magnet and effective for connecting one or the other of said auxiliary cylinders with a source of fluid pressure or both of said auxiliary cylinders with atmosphere according as said magnet is supplied with current of one relative polarity or the other or is deenergized, 70 a manually operable lever, means controlled by said lever for controlling the supply of current to said polarized magnet, an indication relay, and means controlled in accordance with the position of said lock mechanism and the posi- 75

tion of said polarized control magnet for controlling said indication relay.

6. Railway switch operating apparatus comprising a housing containing a pair of spaced drive cylinders containing pistons operatively connected with the switch, lock mechanism for locking said pistons against movement in their extreme positions, a pair of auxiliary cylinders in said housing containing pistons for actuating said lock mechanism and for controlling the supply of fluid pressure to said drive mechanism, a polarized control magnet, valve mechanism operated by said magnet and effective for connecting one or the other of said auxiliary cylinders

with a source of fluid pressure or both of said auxiliary cylinders with atmosphere according as said magnet is supplied with current of one relative polarity or the other or is deenergized, a manually operable lever, means controlled by said lever for controlling the supply of current to said polarized magnet, an indication relay, a circuit controller controlled by said lock mechanism, another circuit controller controlled by said valve mechanism, and means controlled by said two circuit controllers for controlling said indication relay.
